UNITED STATES PATENT OFFICE.

RAPHAEL M. SELDIS, OF NEW YORK, N. Y.

DESIGN FOR THE FUR COVERING OF CAPES, MUFFS, &c.

Specification forming part of Design No. 6,095, dated August 27, 1872.

Specification describing a Design for the Fur Covering of Capes, Muffs, &c., invented by RAPHAEL M. SELDIS, of the city, county, and State of New York.

The nature of my design is fully represented in the accompanying drawing, to which reference is made, in which—

A, Figure 1, represents the skin of an animal dressed with its fur on, and preferably of dark color; B, Fig. 2, representing the skin of an animal also dressed with its fur on, and preferably of white. Certain pieces cut from the white skin are inserted into corresponding openings in the dark skin and sewn to it, as shown in Fig. 1, producing my design; which consists of alternate stripes C D, of white and

dark color, running parallel to each other, the white stripes being pointed or indented at their ends by a dark transverse zigzag stripe, E, and the border stripes F F, which are dark, having white diamond figures G inserted in them.

What I claim as new, and desire to secure by Letters Patent, is—

The design shown and described.

In testimony whereof I have hereunto set my signature this 15th day of July, 1872.

RAPHAEL M. SELDIS.
